UNITED STATES PATENT OFFICE

JOHN J. DOLZER, OF ELM GROVE, WEST VIRGINIA

HOG-SNOUT PULLER

Application filed October 1, 1929. Serial No. 396,543.

The present invention relates to butchering apparatus, and more particularly to a machine for trimming the heads of hogs and the like.

5 An object of this invention is to provide a machine for removing the snouts from the heads of hogs, and to facilitate such operation and admit of the quick and continuous consecutive removal and disposition of the 10 snouts, so that the operation may be carried on without interruption and a relatively large number of heads may be handled per hour, and a larger output be obtained over the present methods than with the apparatus 15 heretofore used.

Another object of the invention is to provide a machine which will pull the snouts from the heads and deposit the snouts upon a work table or the like in position of easy 20 access for further steps in the trimming operation, and thus save considerable labor and time over the old type of pullers which drop the snouts beneath the table into a receptacle 25 and from which the snouts have to be lifted to the table.

A further object is to provide a machine which pulls full length snouts from the heads regardless of the size of the latter, and to thus 30 realize a better yield on the head skins, and further to save labor in the head skinning operation.

A still further object of the invention is to provide a machine possessing the above characteristics and which is of relatively simple 35 construction and easily kept clean, and which has no complicated parts which may readily get out of order, and which insures a relatively low cost in upkeep and operation.

40 A further object of this invention is to provide a machine which is adapted to be driven or operated from any accessible source of power, and which has practically no limit as to its capacity.

45 With the foregoing and other objects in view, the invention will be more fully described hereinafter, and will be more particularly pointed out in the claims appended hereto.

50 In the drawings, wherein like symbols refer

to like or corresponding parts throughout the several views,

Figure 1 is a side elevation, partly in section, of a hog snout puller constructed according to the present invention, the dotted lines showing the position of a head on the machine ready to pull the snout therefrom. 55

Figure 2 is an enlarged fragmentary horizontal section taken through the same substantially on the line 2—2 of Figure 1. 60

Figure 3 is an enlarged fragmentary vertical section taken through a portion of the apparatus with a head of a hog thereon and with the snout properly rolled back ready for removal. 65

Figure 4 is a detail face elevation of the operating drum having the pulling point mounted therein, and showing the outer end of the tripper in retracted position.

Figure 5 is a detail perspective view of the 70 pulling point removed from the drum, and

Figure 6 is a detail perspective view of the support or holding plate upon which the heads of the hogs rest during the operation. 75

Referring to the drawings, the machine may be mounted upon a work table 10 of any suitable construction and which presents a preferably horizontal flat top surface toward one end of which the pulling device is mounted. The pulling device comprises a pair of brackets 11 in the upper ends of which is journaled a transverse shaft 12 and about which is concentrically mounted a drum 13 by means of two or more spaced arms 14. As 80 shown in Figure 2 the arms 14 are spaced apart along the shaft 12 for engaging the drum 13 at or near its opposite lateral edges so as to leave an uninterrupted annular space between the arms 14 and within the drum 13. 85

The drum 13 is provided on its outer peripheral surface with one or more pulling points 15. In the present embodiment a pair of these points is shown, the same being diametrically opposed upon the drum and the points 15 facing in the same direction so as to project downwardly at the forward side of the apparatus, as shown in Figure 1. Each pulling point, as shown in detail in Figure 5, has an attaching plate 16 which is preferably 90

100

countersunk in the surface of the drum 13, as shown in Figure 3, and secured thereto by screws 17 or the like admitting of the quick and easy removal of the points should they become worn or broken. The pulling point is provided with a pair of prongs which are offset outwardly from the plate 16 and extend substantially lengthwise thereof but at a tangent to the plate 16 which preferably is curved lengthwise to conform to the outer surface of the drum. The plate 16 is provided with a longitudinal slot 18 which is in radial and circumferential alignment with the space between the prongs of the pulling point and also with a circumferential slot 19 formed in the drum 13.

The drum 13 is provided at its inner side opposite each pulling point 15 with a pair of brackets 20 between which is pivotally mounted a tripper 21. Each tripper 21 comprises an arm which has a short portion 22 projecting outwardly through the slots 18 and 19 and through the space between the prongs of the pulling point 15.

The outer end of the short portion 22 is provided with a beveled head 23 which extends from the plate 16 outwardly and is adapted to engage the snouts caught upon the prongs for forcing the snouts therefrom as will hereinafter appear. The tripper 21 is mounted upon a pin 24 carried by the adjacent pair of brackets 20 and upon which the tripper is adapted to swing. The inner end of each tripper 20 comprises an elongated arm which extends at an angle to the portion 22 and which extends over one side of shaft 12 so that the shaft 12 serves as a means to limit the swinging of the tripper in one direction, and the inner end of each tripper is provided with a weight 25 adjustable lengthwise thereon and secured in adjusted position by a set screw 26 or the like. The weights 25 are disposed at opposite sides of the shaft 12 so that when the weights are raised above the shaft by the rotation of the drum, the weights fall and operate the trippers 21.

The shaft 12, upon which the drum 13 is fixed, may be provided with a gear wheel 27 at one side of the drum and it may mesh with a pinion 28 supported on a drive shaft 29 which may extend from any suitable source of power or transmission means for driving the pinion and gear wheel. The drum 13 in one practical embodiment may be driven at a speed of approximately 6 revolutions per minute although this speed may be increased or decreased as is found practically desirable. It is also understood that the drum may be turned by any other means than shown as the gear wheel and pinion are merely by way of example and found as one satisfactory means of operating the device.

The table 10 is also provided at its forward end with a rest or support 30 in the form of a plate which is bent transversely near one end

to provide a supporting web 31 located at the inner end of the plate and terminating in a base flange 32 adapted to rest upon and be attached to the table 10. The forward end of the plate 30 has a base flange 33 which is bent at a slight angle to the plate and is adapted to be permanently attached to the table. The plate 30 is thus secured in an inclined position upon the table, and is located between the forward ends of the brackets 11 and beneath the forward side of the drum 13. The plate 30 faces outwardly and upwardly, and is preferably provided with upstanding prongs 34 arranged one near the upper end of the plate and two in spaced relation near the lower end of the plate. The severed head of the hog is adapted to be placed upon this plate with the snout uppermost and toward the drum, and the prongs 34 are adapted to anchor and hold the head from shifting or displacement during the operation of removing the snout from the head.

Referring now to Figure 3 particularly, the head of the hog is prepared for the removal of the snout by marking or slitting the skin at opposite sides of the head along the line 35 so as to direct the severance of the snout 36 with the skin and the portions of snout meat 37 which are located in the cavities at opposite sides of the skull 38, the snout 36 when initially marked or cut is turned back in the position shown in Figure 3. The head is placed upon the support 30 with the snout uppermost and toward the drum 13. The heads may be successively positioned and removed upon the support 30 with considerable ease and speed so that as the drum turns the pulling points 15 are successively brought into engagement with the snouts 36 and quickly strip the snouts with their adjacent portions from the heads.

As the pulling points 15 move downwardly with the drum, the weights 25 fall below the shaft, as shown in Figure 1, and the tripper heads 23 are held in retracted position at the inner ends of the pulling points 15. The pulling points 15 travel downwardly and carry with them the snouts 36 until they reach the opposite or rear end of the table 10 when the weights 25 are at that time moved into position above the shaft 12 and fall toward or on the same, and move the tripper heads 23 outwardly in the pulling points 15 and eject or remove the snouts therefrom. The snouts thus fall upon the upper surface of the table 10 in position of easy access of the trimmers for further operation in skinning and otherwise treating the snouts.

It is obvious that various changes and modifications may be made in the details of construction and design of the above specifically described embodiment of this invention without departing from the spirit thereof, such changes and modifications being re-

stricted only by the scope of the following claims.

What is claimed is:—

1. A hog snout puller, comprising a drum, means for turning the drum, a pair of pulling points mounted in the drum, means for supporting the head of a hog adjacent one side of the drum with the snout of the head in the path of the pulling points for removal of the snout from the head, and means for removing the snouts from the pulling points at the opposite side of the drum.

2. A hog snout puller, comprising a drum, means for turning the drum, a pulling point mounted on the drum, a support at one side of the drum adapted to receive the head of a hog with the snout in the path of the pulling point, and a tripper carried on the drum and operable upon the travel of the pulling point and the opposite side of the drum for removing the snout from the pulling point.

3. A hog snout puller, comprising a drum, a table supporting the drum, a pair of pulling points disposed upon the opposite sides of the drum and facing in the same direction, a supporting plate mounted on the table at one side of the drum for supporting the head of a hog with the snout uppermost and in the path of the pulling points, means for turning the drum to engage the adjacent pulling point with the snout and pull the same from the head and carry the snout to the opposite side of the drum, and a gravity actuated tripper mounted on the drum to eject the snout from the pulling point when at said opposite side of the drum and deposit the snout on the opposite side of the table, said tripper being automatically retracted during the turning of the drum to engage the next snout.

4. A hog snout puller, comprising a movable carrier, a pulling point on the carrier, means for supporting the head of a hog in the path of the point, means for actuating the carrier to engage the point in the snout and pull the latter from the head, said carrier adapted to remove the point with the snout to a position remote from the supporting means, and a tripper for removing the snout from the pulling point when in said remote position.

5. A hog snout puller, comprising a table, a pair of brackets rising from one end of the table, a shaft mounted across said brackets, a drum mounted on the shaft between the brackets, pulling points mounted on the outer surface of the drum and extending in one direction thereon, means for turning the drum in said direction, an outwardly and upwardly fixed support mounted on said end of the table in position to support the head of a hog with the snout at the upper end of the head and extending toward the drum in the path of said pulling points, the adjacent pulling points adapted to engage said snout

and strip the same from said head and to carry the snout to the opposite end of the table, pivoted arms mounted in the drum and having tripper heads on their outer ends and weights upon their inner ends, said weights adapted to move downwardly as the puller points engage the snouts and adapted to drop in reverse direction when the pulling points with the snouts move to the opposite side of the drum for ejecting the snouts and depositing the same upon said opposite end of the table.

6. A hog snout puller, comprising a drum, means for rotatably mounting the drum over a table, an inclined support having upstanding prongs for supporting the head of a hog at one side of the drum, pulling points mounted on the drum adapted upon rotation of the drum to engage the snouts of the head on said support and carry the snouts to the opposite side of the drum, and a gravity actuated tripper mounted on the drum for each pulling point and adapted to be overthrown by the turning of the drum to retract the tripper during engagement with a snout and to eject the snout from the pulling points at the opposite side of the drum.
